UNITED STATES PATENT OFFICE.

OSCAR H. PIEPER AND ALPHONSE F. PIEPER, OF ROCHESTER, NEW YORK.

DESIGN FOR A VALVE-FITTING.

48,870.

Specification for Design.

Patented Apr. 11, 1916.

Application filed November 20, 1915. Serial No. 62,657. Term of patent 14 years.

To all whom it may concern:

Be it known that we, OSCAR H. PIEPER and ALPHONSE F. PIEPER, both of Rochester, in the county of Monroe and State of New York, have invented a new, original, and ornamental Design for a Valve-Fitting, of which the following is a specification and of which the accompanying drawings are a representation.

In the drawings: Figure 1 is a plan view

of a valve fitting, showing our new design. Fig. 2 is a front elevation.

We claim:

The ornamental design for a valve fitting, as shown.

OSCAR H. PIEPER.
ALPHONSE F. PIEPER.

Witnesses:

V. R. HUMPHREYS,
M. E. ZIMMER.
